UNITED STATES PATENT OFFICE

OTTO A. HOKANSON AND JAMES F. KOCA, OF WOODSTOCK, ILLINOIS, ASSIGNORS TO
WOODSTOCK TYPEWRITER COMPANY, OF WOODSTOCK, ILLINOIS, A CORPORATION
OF ILLINOIS

REMOTE CONTROL MECHANISM

Application filed October 19, 1925. Serial No. 63,501.

This invention relates to remote control mechanism especially applicable to adjusting radio apparatus such as radio antennæ, dials and other adjustable parts.

5 The object of the invention is to provide means for adjusting movable parts which may be operated at any convenient position remote from the part to be adjusted.

10 The invention is exemplified in the combination and arrangement of parts shown in the accompanying drawings and described in the following specification, and it is more particularly pointed out in the appended claims.

15 In the drawings—

Fig. 1 is an elevation of the remote control dial;

Fig. 2 is a plan view, on a larger scale, of the dial shown in Fig. 1;

20 Fig. 3 is a vertical section through the remote control dial;

Fig. 4 is a horizontal section substantially on line 6—6 of Fig. 3;

25 Fig. 5 is an end view of a socket for receiving the electrical connection for the mechanism shown in Fig. 3;

Fig. 6 is a section substantially on line 8—8 of Fig. 4;

30 Referring to the drawings, 62 designates a base upon which there is mounted a housing 63. Mechanism for producing electrical impulses is contained within the housing 63 and comprises a star-wheel 67 secured to a spindle 68 which carries the dial 64. The star-wheel 67 is provided with a series of points 69 which engage rollers 70 and 71 mounted on fingers 72 and 73 which are carried by pivot screws 74 and 75, respectively, secured to a plate 76 which is supported on the base 62 by suitable lugs 77. The fingers 72 and 73 are provided with springs 78 and 79, respectively, having contact members 80 and 81 for engaging a contact 82 carried on an arm 83 which is pivoted on the central spindle 68.

35 The arm 83 has limited rotary movement about the spindle 68, the movement being controlled by a slot 84 which is engaged by a pin 85 on the end of the arm opposite the contact member 82. The member 83 has a laterally projecting lug to which

a link 86 is connected by a pivot 87. A roller 88 is journaled on the link 86 and engages the notches between the points 69 on the star-wheel. A spring 89 holds the roller 88 in contact with the notches. The rollers 70 and 71 are also yieldingly held in the notches on the star-wheel by springs 90 and 91. A stop 92 is formed on the star-wheel 67 and engages a pin 93 extending downwardly from the case 63 to prevent more than one complete rotation of the star-wheel. If the dial 64 and the star-wheel 67 is rotated in a counter-clockwise direction from the position shown in Fig. 4 it will be apparent that each time one of the points 69 passes the roller 70 the contacts 80 and 82 will be moved into engagement with each other. If the dial is turned to move two points past the roller 70, an antenna (not shown) which may be operatively connected with the switch will be accordingly turned a corresponding amount. If a half revolution is imparted to the dial the antenna will be turned 90° and if a complete revolution is imparted to the dial the antenna will be turned 180°. If it is desired to reverse the movement of the antenna it is only necessary to turn the dial in the opposite direction. The first effect of this will be to swing the arm 83 in a clockwise direction, as viewed in Fig. 4, to bring the contact 82 opposite the contact 81. This is effected by the roller 88 which is carried to the right in Fig. 4 by the teeth 69 until its movement is limited by the slot 84. Further rotation in the same direction will produce connection between the contacts 81 and 82 each time a point 69 passes the roller 71. The contact 81 may be connected with one of a pair of magnets (not shown) so that the impulses imparted by this connection produce rotation of the antenna in the opposite direction from that imparted by the other of said magnets. Any suitable wiring circuit may be employed which connects the contact 80 in the circuit with one of the magnets and the contact 82 in the circuit of the other magnet.

40 In the forms shown, a cable 94 having 4 conductors is employed. This cable is provided with plugs 95 for entering sockets 96 connected by conductors to the proper appa-

status to which it is desired to connect the plugs 95. One of the sockets 96 may be connected with the positive terminal of a battery and the other connected with the negative terminal. The other two sockets will lead to the magnets. The plug 95 which is connected to the socket 96 of the negative terminal of the battery leads to a connection 97, grounded on the base plate 76 of the 10 housing for the dial mechanism. The magnets are provided with conductors 98, one conductor from each magnet being connected with the positive terminal of the battery while the other conductors extend through 15 the cable 94 to their respective contacts 80 and 81. When a contact 80 or 81 engages the contact 82 the circuit will be completed through the arm 83, the plate 76 and the connection 97, back to the negative terminal 20 of the battery. The current will then flow from the battery to the corresponding magnet, from the magnet through the conductor and cable 94 and the contact 82, back to the battery. When the dial and antenna have 25 once been arranged in proper relation to each other it will be apparent that the position of the dial will always indicate the position of the antenna since the two will always move in unison with one another. The antenna is held against movement by external force and can only be moved when operated through rotation of the dial. Any movement of the dial will cause a corresponding rotation of the antenna so long as current is 30 supplied from the source of supply.

Mechanism is provided to prevent rotation of the dial in case the source of current supply should fail. This comprises a magnet 99 having a spring pressed plunger 100, as 40 shown in Fig. 6, provided with a pin 101 arranged to enter openings 102 in the star-wheel 67. One opening is provided for each of the points 69. Current is supplied to the magnet 99 through a switch 103 having 45 a push-button 104 extending upwardly through the casing 63. One terminal of the switch 103 is connected through the cable 94 to the positive terminal of the battery. The other terminal of the switch is connected 50 through the magnet 99 to the frame plate 76 which, as explained before, is connected to the negative terminal of the battery. When the push-button 104 is depressed the magnet 99 will be energized if the source of current 55 supply is operative. This will retract the plunger 100 and permit rotation of the star-wheel 67. If for any reason the source of current supply is inoperative the plunger will not be retracted on depression of the 60 button 104 so that the dial cannot be rotated until the source of current supply is restored. This prevents rotation of the dial when the current is shut off.

In the form of the invention shown in Figs. 65 1 to 6, inclusive, the antenna can be rotated

only through 180° so that there is no possibility of winding the lead wires about the mast of the antenna.

It will be apparent that the mechanism shown as applied to an antenna mast may be equally well applied to other rotary members to permit them to be adjusted from a remote control station. Frequently it is desirable to be able to regulate the receiver without the necessity of leaving one's position and going to the receiving set. The control switch may be placed on a dining-room table or at any other desired position remote from the receiving set and the receiving set can be controlled as readily as if the person were 70 directly at the receiving cabinet.

The invention provides relatively simple and highly efficient means for controlling an electric circuit by remote control. The remote control-dial consists of relatively few 75 parts which, when operated, produce impulses in the circuit of a magnet to rotate a member such as a radio antenna.

Changes may be made in the form, construction, and arrangement of parts without departing from the spirit of the invention or sacrificing any of its advantages, and the right is hereby reserved to make all such changes as fairly fall within the scope of the 80 following claims.

We claim:—

1. A control device for an electric circuit comprising a pair of contact members arranged in different circuits, a third contact member pivotally mounted to move in two directions and movable into different positions to cooperate with either one or the other of said first-mentioned contact members, means to limit the pivotal movement of the third contact member in both directions, and means for engaging and disengaging said third contact member with either of said first contact members while in position to co-operate therewith.

2. A device for controlling electric circuits comprising a pair of contact members connected with different circuits, of a common contact member arranged to be moved into position to co-operate with either one or the other of said first-mentioned contact members, a contact closing means, and means operated by said contact closing means for shifting said common contact member, said contact closing means being arranged to operate successively with said common contact member while in co-operation with either of said pairs of contact members.

3. A device for controlling electric circuits comprising a pair of spaced contact members, a third contact member movable into registration with said first-named contact members respectively, a rotary member having spaced projections thereon for moving said first-mentioned contact members, and means

actuated by said rotary member for shifting said third contact member from one to the other of said first-mentioned contact members when the direction of rotation of said 5 rotary member is reversed.

4. The combination with a rotary member having spaced projections on the periphery thereof, of an arm having limited movement about the axis of said rotary member, a contact member carried by said arm, and means 10 yieldingly carried by said arm for engaging the projections on said rotary member to cause said arm to be moved by said rotary member to the limit of its movement in either 15 direction when said rotary member is moved in that direction.

5. The combination with a rotary member having spaced projections on the periphery thereof, of a pair of peripherally spaced contact members disposed adjacent said rotary member, a pivoted arm having angular movement about the axis of said rotary member in two directions, means on the arm for limiting 20 the pivotal movement of said arm in both directions, a contact member carried by said arm and movable thereby into registration with either of said spaced contact members, and yielding means on said arm engaging 25 said rotary member to move said arm in unison with said rotary member to the limit of its movement in either direction for shifting the position of the contact member carried by 30 said arm when the direction of rotation of 35 said rotary member is reversed.

6. Means for controlling an electric circuit comprising a revolvably mounted member, a longitudinal pivoted arm having operable contacting engagement with said member, a contact carried by one end of said arm, a pair 40 of contacts with which the first named contact makes selective contacting engagement, means on the other end of said arm and engaging the first-named member for limiting 45 the pivotal movement of said arm, and means for rotating the revolvably mounted member for shifting the arm to bring the contact on said arm into electrical engagement with either of said other contacts.

7. Means for controlling an electric circuit comprising a revolvably mounted member, a longitudinal pivoted arm having operable engagement with said member, a contact carried by one end of said arm, a pair of contacts 55 with which the first named contact makes selective engagement, means on the other end of said arm for limiting the pivotal movement thereof, means for rotating the revolvably mounted member for shifting the arm to bring the contact on said arm into electrical engagement with either of said other contacts, and means for normally maintaining 60 said contacts out of electrical contact with each other.

In testimony whereof we have signed our names to this specification on this 16th day of October A. D., 1925.
